UNITED STATES PATENT OFFICE

135,846

DESIGN FOR A SHEEP SHEARING DEVICE

Vincent A. Wilcox, Modesto, Calif., assignor to
The Pneumatic Shear Company, Turlock,
Calif., a corporation of California

Application February 23, 1942, Serial No. 105,953

Term of patent 14 years

To all whom it may concern:

Be it known that I, Vincent A. Wilcox, a citizen of the United States and a resident of Modesto, county of Stanislaus, State of California, have invented a new, original, and ornamental Design for a Sheep Shearing Device, of which the following is a specification, reference being had to the accompanying drawing, forming part thereof.

Figure 1 is a plan view of a sheep shearing device showing my new design.

Figure 2 is a bottom view thereof.

Figure 3 is a side elevational view thereof.

Figure 4 is a front elevational view thereof.

I claim:

The ornamental design for a sheep shearing device, substantially as shown.

VINCENT A. WILCOX.
